TYPEWRITING MACHINE

Carl Gabrielson and Edson George Moshier,
Syracuse, N. Y., assignors to L C Smith &
Corona Typewriters Inc., Syracuse, N. Y., a
corporation of New York

Application August 30, 1935, Serial No. 38,520

9 Claims. (Cl. 197—33)

1. The invention relates to improvements in typewriting machines and more particularly to means for regulating or adjusting the touch on the finger keys of the type actions of the machine.

5 2. The invention makes provision for simultaneously and uniformly adjusting or varying the touch of all of the type action keys and also makes provision for adjusting or varying the touch of each of the type action keys independently of the others.

10 The invention provides simple, efficient and easily operable means readily accessible to the typist for simultaneously and uniformly adjusting or varying the normal tension of all of the type action return springs, and means for limiting the range of adjustment of the tension of the return springs.

15 To the foregoing and other ends which will appear the invention consists in the features of construction, arrangements of parts and combinations of elements set forth in the following description of preferred illustrative embodiments of the invention and particularly pointed out in the appended claims.

20 3. In the accompanying drawing,

Fig. 1 is a fragmentary side elevation of a typewriting machine with certain parts broken away to better illustrate the improvements, only so much of the machine being shown as is necessary for a clear understanding of the invention;

25 Fig. 2 is a detail sectional view on the line 2—2 of Fig. 3;

Fig. 3 is a detail sectional view on the line 3—3 of Fig. 2;

30 Fig. 4 is a detail sectional view on the line 4—4 of Fig. 1; and

Fig. 5 is a fragmentary side elevation of the machine, with certain parts broken away, and showing a modified construction.

35 4. The drawing shows the invention embodied in a known typewriting machine, namely the L C Smith machine, but may be embodied in various other kinds of typewriting machines to which the improvements are applicable.

40 5. In the construction shown each type action comprises a key lever 10 provided at its forward end with a finger key 11 and fulcrumed at its rear end on a fulcrum bar 12 which is rigidly held to the main frame 13 of the machine. Each key lever actuates its associated one of the type bars 14, the type bars being pivotally mounted in the known manner on a suitable type bar segment 15 mounted in the machine frame. Each type bar is connected by a pull link 16 to the upper end of an associated sub-lever 17. The sub-

5 levers 17 are fulcrumed on a pivot member 18 carried by a support 19 fixed to the main frame of the machine. Each sub-lever is connected to its associated key lever by a pull link 20. Each type action is returned, after depression of its key, by a helical contractile type action return spring 21, there being one of the springs 21 for each type action, and said springs normally holding the front portions of the key levers engaged under a suitable stop bar 22 held to the machine 10 frame. Each spring 21 extends upwardly from its associated key lever, the lower end of the spring being hooked in a suitable aperture near the rear end of the key lever forward of the fulcrum of the key lever. The springs 21 are arranged in a 15 straight line or row transversely of the machine.

20 The improved means whereby the normal tension of the springs may be adjusted or varied to vary or regulate the touch of the type action keys will now be described. Each of the springs 20 21 is individually adjustably anchored at its upper end to an anchor device or touch regulating device in the form of a composite or two-part plate which extends transversely of the machine above the rear portions of the key levers and 25 which is rockable up and down to simultaneously and uniformly vary the normal tension of all of the springs. The anchor device or touch regulating device, as shown, comprises a front bar 23 arranged in partly overlapped relation with a 30 rear bar 24, the overlapping portions of said two bars being rigidly held together by a plurality of screws 25 to form a composite two-part plate. The rear bar 24 is journaled at its ends adjacent its rear edge on the inner ends of two bearing 35 screws 26 (Fig. 4) tapped into opposite sides of the main frame of the machine, the composite plate or anchor device being thus supported to rock up and down in the main frame about a horizontal axis extending transversely of the machine. 40

45 A series of return-spring tension adjusting screws 27, one for each key lever, extend loosely down through apertures 28, (Fig. 2) in the front bar 23 of the anchor device, said apertures being arranged in a single row transversely of the machine. The heads of screws 27 rest on the upper face of bar 23 and the threaded shanks of the screws are screwed into the upper end portions of the helical return springs 21 to anchor the springs at their upper ends to the rockable anchor device 50 23—24 adjacent the front edge of the anchor device. By screwing any one of the screws 27 more or less within the upper end of its companion spring 21, the tension of that spring may be varied independently of all the other return springs. 55

Uniform touch for all the type action keys may thus be obtained.

It will be obvious that by rocking the anchor device 23-24 upward the normal tension of all 5 of the return springs will be simultaneously and uniformly increased and by rocking the anchor device downward the normal tension of all of the return springs will be simultaneously and uniformly decreased.

10 For rocking the anchor device up and down and holding it in desired adjustably rocked position the following means are provided. An upwardly extending rock arm 29 is fixed at its lower end to the right hand end of bar 24 and is preferably provided at its upper end with an anti-friction roller 30 journaled on a pivot stud 31 carried by the rock arm, said pivot stud extending horizontally transversely of the machine. A horizontal shaft 32 extending transversely of the machine is journaled in the main frame 13 above the anchor device at the right hand side of the machine, said shaft extending through a standard forming part of the right hand side of the machine frame. Fixed on the inner end of shaft 32 is a cam 33 having a spiral periphery 33^a to which the roller 30 on arm 29 is held by the pull of the return springs 21. A finger wheel 34, preferably having a scalloped periphery as shown, is fixed on the outer end of shaft 32, where it is conveniently accessible to the typist for turning the plate cam 33 in either direction to cause the cam follower rock arm 29 to swing forward or rearward as desired to rock the anchor device 23-24. Preferably the cam operating finger wheel 34 is provided with indicating numerals such as "0" to "9" on its outer face and a suitable indicator or pointer 35 is fixed on the right hand side of the frame at the outer side of the frame adjacent said wheel for cooperation with the numbered face of the 40 wheel.

The follower roller 30 on follower rock arm 29 contacts the cam preferably in rear of the cam, and also moves in and out substantially radially of the cam axis so that the arm 29 will remain in 45 any adjusted position to which it is shifted by rotation of cam 33. Preferably also cam 33 is provided with an outward extension or lobe 33^b between the low and high ends of its spiral roller-engaging peripheral surface 33^a, the opposite sides 50 of which lobe 33^b preferably are flared or curved outwardly away from each other to provide hook-like surfaces 33^c at the high and low ends of surface 33^a engageable with roller 30 to positively arrest rotation of the cam and positively limit 55 rotation of the cam to less than one revolution. The cam is thus oscillatable between fixed limits to rock the anchor device between predetermined fixed limits.

To decrease the effort required to actuate the 60 cam and rock the anchor device, and to reduce wear of the cam, means, preferably in the form of a pair of counterbalancing springs 36, are provided for counterbalancing or counteracting the pull upon the anchor device 23-24 of the series of 65 return springs 21. In the construction shown in Figs. 1 to 4, the two contractile helical springs 36 are anchored at their lower ends to opposite ends of bar 23 at the front corners of anchor device 23-24 and are anchored at their upper ends 70 to the main frame 13 of the machine by hooking their upper ends through apertures in the frame. The pull of the pair of springs 36 does not exceed, and preferably is less than, the opposing pull of the series of return springs 21. In the construction 75 shown in Fig. 5 provision is made for adjust-

ing the pull of springs 36 by anchoring the upper ends of the springs 36 to the lower ends of a pair of substantially vertically extending and adjustable spring anchor screws 37 extending loosely through apertures 38 in fixed parts of the main frame 13. As shown in Fig. 5, the upper ends of springs 36 are hooked through apertures in the lower ends of screws 37. Each screw 37 has threaded thereon an adjusting nut 39. Said nuts 39 are held down against the frame by the pull 10 of springs 36. By holding the screws 37 against rotation and screwing the nuts 39 up and down the normal tension of the springs 36 may be varied as desired. Except as just above described, the modified construction shown in Fig. 5 corresponds with the construction shown in Figs. 1 to 4.

What we claim is:

1. A typewriting machine having, in combination, a main frame, type actions supported in the main frame and each including a key lever fulcrumed in the main frame and a contractile helical return spring anchored at one end thereof to the key lever, an anchor device having a series of spring anchor screws extending therethrough and each threaded into the other end of a different one of the return springs, said anchor device extending transversely of the main frame and being supported therein for rocking of the anchor device about a horizontal axis extending transversely of the machine to vary the normal stress of the return springs, a cam follower rock arm fixed to said anchor device, a plate cam with the periphery of which said rock arm coats, a horizontal shaft journaled in the main frame and extending transversely thereof, said cam being fixed on said shaft and said shaft extending outwardly from said cam to one side of the frame and having a finger wheel fixed on its outer end. 40

2. A typewriting machine as claimed in claim 1, wherein said cam has a spiral peripheral surface coactive with the rock arm to rock the arm and has between the high and low ends of said spiral surface a lobe extending outwardly relatively to the axis of the cam, said lobe being coactive with the rock arm to positively limit the extent of rotation of the cam in both directions. 45

3. A typewriting machine having, in combination, a main frame, key-operated type actions supported in the main frame, an anchor device, contractile type action return springs all connected at one end with said anchor device and each connected at the other end with a different one of the type actions, said anchor device being pivotally supported in the main frame for rocking thereof about a horizontal axis extending transversely of the frame to vary the normal stress of the springs, a rock arm fixed at one end to the anchor device, a shaft journaled in the frame and extending parallel to the pivotal axis of the anchor device, a finger wheel fixed on said shaft, and a plate cam fixed on said shaft and coactive with the rock arm to rock said arm. 50

4. A typewriting machine having, in combination, a main frame, key-operated type actions supported in the main frame, an anchor device, contractile type action return springs all connected at one end with said anchor device and each connected at the other end with a different one of the type actions, said anchor device being pivotally supported in the main frame for rocking thereof about a horizontal axis extending transversely of the frame to vary the nor- 70

mal stress of the springs, a rock arm fixed at one end to the anchor device, a shaft journalled in the frame and extending parallel to the pivotal axis of the anchor device, a finger wheel fixed 5 on said shaft, and a plate cam fixed on said shaft and coactive with the rock arm to rock said arm, and contractile spring means connected with the frame and anchor device to oppose the pull of the type action return springs 10 on the anchor device.

5. A typewriting machine having, in combination, a set of type actions having operating keys, a set of contractile return springs for said actions, a shiftable device to which and to said 15 actions the opposite ends of said set of springs are connected and which device is supported for shifting movement thereof which will simultaneously and uniformly vary the lengths of the 20 springs, a member supported to turn in contactive engagement with said device about a fixed axis and in a fixed plane, the contractive parts of said member and device being effective to hold 25 said device in different shifted positions varied by the turning of said member and to positively limit turning of said member in both directions about its axis, and a handle connected with 30 said member for turning of the latter in opposite directions by the handle.

6. A typewriting machine having, in combination, a set of type actions having operating keys, a set of contractile return springs for said actions, a shiftable device to which and to said actions the opposite ends of said set of springs are connected and which device is supported for 35 shifting movement thereof which will simultaneously and uniformly vary the lengths of the springs, a cam supported to turn in opposite directions about a fixed axis and in a fixed plane and engaged with a part of said shiftable device 40 to shift the latter into and hold it in different ones of its spring-length-varying positions against the pull of the return springs, said cam having means automatically engageable with said part of said shiftable device to positively 45 limit rotation of the cam in both directions about the cam axis, and a handle connected with said cam for turning of the cam in opposite directions by the handle.

7. A typewriting machine having, in combination, a set of type actions having operating keys, a set of contractile return springs for said actions, a shiftable device to which and to said actions the opposite ends of said set of springs are connected and which device is supported for 50 shifting movement thereof which will simultaneously and uniformly vary the lengths of the springs, a key-touch control handle mounted for turning thereof in opposite directions in a fixed plane about a fixed axis, and means oppositely

5
rotative by said handle in contact with said device and effective on the device to positively limit turning of the handle in both directions about its axis and to hold said shiftable device stationary against the pull of the springs in different ones of the spring-length varying positions of said device.

8. A typewriting machine having, in combination, a set of type actions having operating keys, a set of contractile return springs for the type 10 actions, a shiftable device with which and the type actions the opposite ends of the return springs are connected and which device is supported for shifting movement thereof which will simultaneously and uniformly vary the lengths 15 of the return springs, a thrust member supported to turn in a fixed plane about a fixed axis and against which said device is constantly yieldably held abutted by the pull of the return springs, spring means constantly effective on said device 20 to oppose the pull of the return springs on the device without causing separation of said device and thrust member, and a handle connected with the thrust member for turning of said member in opposite directions about its axis, said 25 thrust member being effective on said device to hold the latter stationary against the pull of the return springs in different spring length varying positions varied by turning of the thrust member by the handle. 30

9. A typewriting machine having, in combination, a set of type actions having operating keys, a set of contractile return springs for the type actions, a shiftable device with which and the type actions the opposite ends of the return 35 springs are connected and which device is supported for shifting movement thereof which will simultaneously and uniformly vary the lengths of the return springs, a thrust member supported to turn in a fixed plane about a fixed axis and against which said device is constantly yieldably held abutted by the pull of the return springs, spring means constantly effective on said device 40 to oppose the pull of the return springs on the device without causing separation of said device and thrust member, said thrust member being effective on said device to hold the device in different spring length varying positions varied by turning of the thrust member about its axis, said device being effective on the thrust member 45 to positively limit turning of the thrust member in both directions about the axis of said member, and an operating handle connected with the thrust member for turning of the member in opposite 50 directions about its axis by opposite turnings of the handle. 55
